DESIGN FOR A CLASP FOR HANDBAG
FRAME OR THE LIKE

Robert T. Sporman, Essex County, N. J., assignor to The J. E. Mergott Co., Newark, N. J., a corporation of Delaware

Application March 5, 1947, Serial No. 137,369

Term of patent 3½ years

(Cl. D87—2)

To all whom it may concern:

Be it known that I, Robert Thomas Sporman, a citizen of the United States of America, residing in the county of Essex and State of New Jersey, have invented a new, original, and ornamental Design for a Clasp for Handbag Frame or the like, of which the following is a specification, reference being had to the accompanying drawing, forming a part thereof.

Fig. 1 is a side elevation of the clasp for handbag frame or the like, showing my new design;

Fig. 2 is a plan view of the clasp shown in Fig. 1;

Fig. 3 is an end view of the clasp in open position.

I claim:

The ornamental design for a clasp for handbag frame or the like, as shown.

ROBERT T. SPORMAN.
